UNITED STATES PATENT OFFICE.

GEORGE FRAIN, OF KOKOMO, INDIANA.

LETTER AND BUNDLE TIE.

1,316,293.

Specification of Letters Patent.

Patented Sept. 16, 1919.

Application filed November 5, 1917. Serial No. 200,306.

To all whom it may concern:

Be it known that I, GEORGE FRAIN, citizen of the United States of America, residing at 1120 South Buckeye street, Kokomo, in the 5 county of Howard and State of Indiana, have invented certain new and useful Improvements in Letter and Bundle Ties, of which the following is a specification, reference being had therein to the accompanying 10 drawing.

The object of the invention is to provide a letter and bundle tie, which will securely hold a bundle of letters or other bundle securely and at the same time, so construct 15 the clamping means that the same can be easily and quickly released or tightened as the number of letters in the bundle is decreased or increased.

A further object is to so construct the 20 clamping means of the tie, that there will be a double clamping of the strap that goes around the package of letters.

A further object of the invention is to construct the clamping member proper in two 25 parts, the main plate being provided with means for securing the clamping plate thereto, said clamping plate having up-standing side flanges engaging the end of the main plate thereby preventing an up- 30 ward bending of the clamping plate, said clamping plate having a double member carried in bearings of its upstanding flanges.

A further object is to provide a letter or 35 bundle tie clamping member wherein a double clamping is accomplished and wherein a pull upon the free end of the strap will release the double clamping member.

A further object is to provide means for 40 securing the permanently fixed end of the strap, so that, the same may be securely held between teeth which form strap engaging means, but of such a construction that they may be easily bent downwardly and 45 the strap removed for renewing the same.

Other objects will appear and be better understood from the embodiment of the invention of which the following is a specification, reference being had to the accompanying drawings forming part thereof, in 50 which:—

Figure 1 is a perspective view of the letter or bundle tie, showing the same applied to a bundle.

Fig. 2 is a sectional view on line 2—2 of Fig. 1.

Fig. 3 is a top plan view of the clamp, the strap being eliminated to better show the construction.

Fig. 4 is a perspective view of the plate 60 and clamping member.

Fig. 5 is a top plan view of the clamp, showing the same stamped from a single piece of sheet metal.

Fig. 6 is a sectional view on line 6—6 of Fig. 5.

Referring to the drawings 1 designates a package of letters or bundle and 2 the clamp as a whole. The clamp 2 comprises a body member 3, which is provided at its ends 70 with rolls 4 and 5. The body member 3 is provided near one end with a plurality of zigzag slits 6 and 7, which form a series of transverse teeth 8, which are bent downwardly. One end of a strap 9 is passed upwardly through the slot 6 and then downwardly through the slot 7 after which the teeth 8 are bent into engagement with the strap adjacent the slots 6 and 7. From this construction it will be seen that one end of 75 the strap will be securely fastened to the plate 3, it will also be seen that the strap may be easily removed by inserting a tool into the slots from the top of the plate 3 and pressing downwardly upon said tool. 80

Mounted in the roll 5 of the plate 3 is a metal loop 3^a. The extension forming the roll 4 of the body member 3 extends through a slot 10 in the clamping plate 11, said clamping plate having an extension 12, 90 which is securely clamped and held against displacement by the roll 4. The clamping member 11 comprises the plate 12, which is disposed lower than the plate 3 so that the roll 4 will form an abutment. The clamping plate 12 has a pair of upstanding ears 13, one end of each of said ears engaging the plate 3 as at 14, thereby providing means for preventing the plate from being easily 95 bent during the tightening operation of the strap. Mounted in bearings 14 of said upstanding ears are the pintles 15 of the pivoted double clamping member 16. The clamping member 16 has a downwardly extending member 17 adapted to engage the 100 strap 9, after it has been passed around the bundle and clamp the same against the plate 12. The rearwardly extending toothed member 18 of the clamp 16, engages and 105 clamps the strap as at 19 against the roll 4, 110 which auxiliary clamping is of value when there is a great deal of resiliency in the let-

ters or the package being clamped. The free end of the strap is then passed through the loop 3^a.

When it is desired to release the strap the same is grasped by the fingers as at 20, then the free end of the strap is pulled in a direction away from the double clamp. This pulling action causes the strap to move toward the loop end of the main plate and as the teeth of the member 17 are in engagement with the strap, the clamping member as a whole will be caused to turn on its pintles until the member 17 has passed through the vertical, at which time the members 17 and 18 will be out of engagement with the strap. When the double clamp is out of engagement with the strap the free end of the strap will freely pass under double clamp and the package of letters released. During the unclamping operation the necessary slack is obtained by the squeezing together of the letters, which is caused by the pulling action on the free end of the strap.

In Figs. 5 and 6 the members 3 and 11 have been made in one piece. In this form the roll 4 has been eliminated and an abutment 4^a forms means for the strap to be clamped against.

Having thus described my invention what I claim and desire to secure by Letters Patent is:—

1. A bundle tie comprising a clamp formed from two plates, a body plate having toothed slots at one end for securing one end of the strap, a clamping plate rigidly secured to the other end of said body plate and disposed below said body plate, upstanding lugs carried by said clamping plate and engaging one end of the body plate and means carried by said clamping plate for securely clamping the free end of the strap.

2. A bundle tie comprising a clamp formed from two plates, a body plate having rolls at each end thereof, one of said rolls having a clamping plate rigidly secured thereto and disposed lower than the body plate, a pivoted double clamping member carried by said clamping plate, a strap secured to one end of the body plate, its free end being clamped between one jaw of the pivoted clamping member and the clamping plate and its free end also clamped between the other jaw of the pivoted clamping member and the plate member roll.

In testimony whereof I hereunto affix my signature.

GEORGE FRAIN.

Copies of this patent may be obtained for five cents each, by addressing the "Commissioner of Patents, Washington, D. C."
